United States Patent Office

Des. 189,020
Patented Oct. 18, 1960

189,020

RESTAURANT BUILDING

James N. Lindenberger, Evanston, Ill., assignor to
Fred E. Koehler, Roselle, Ill.

Filed Oct. 29, 1958, Ser. No. 53,203

Term of patent 14 years

(Cl. D13—1)

FIG. 1

FIG. 2

FIG. 3

FIG. 4

Fig. 1 is a side elevational view of a restaurant building showing my new design;

Fig. 2 is a perspective view of the building;

Fig. 3 is an elevational view of the building taken at an angle of 45° to the elevational view of Fig. 1; and

Fig. 4 is a top plan view.

The essential features of the design reside in the portions shown in full lines.

I claim:

The ornamental design for a restaurant building, substantially as shown and described.
